UNITED STATES PATENT OFFICE.

MARK E. FERNALD, OF SOUTHBORO, MASSACHUSETTS, ASSIGNOR TO C. C. BLAKE,
INCORPORATED, OF BOSTON, MASSACHUSETTS, A CORPORATION OF NEW YORK.

AUTOMATIC SHOE MACHINE.

Application filed September 13, 1922. Serial No. 587,941.

This invention relates to automatic shoe machinery of the class in which a leader is employed as a guide to cause a proper operation of the tools during a relative traverse of the tool and shoe being operated upon. In automatic shoe machinery of this class the shoe is mounted upon a jack and the simpler mode of operation is to rotate the jack and leader to cause a transfer of the tool along the last, shoe, or part of a shoe, as the case may be. In one type of automatic shoe machinery, embodying these principles, the leader has the general form, in plan, of a shoe sole and the jack is so assembled therewith that the bottom of the last on which the shoe is built is exactly superposed above the leader. The present invention relates more particularly to means for mounting the leader and the shoe and for assembling them in the relation just described.

One system of making shoes by automatic machinery contemplates providing each machine, for performing a distinct operation on the shoe, with a leader for governing the relative movements of the shoe and the tool to transfer the point of operation of the tool about the shoe, and then associating a jacked last or shoe with each leader, the jack being readily attached to the leader support in position for the operation to be performed and as readily detached for transfer to the machine for performing the next operation.

The general object of the present invention is to provide, in a shoe making system of the character described, means for insuring the proper relation of the work on the jack to the leader when one is brought to the other, and this without the exercise of any skill on the part of the operator. The invention aims to make certain that, when the jacked work is assembled with the leader, all points on the contour of the work to be operated upon, such as the edge of the insole for example, will be exactly superposed on homologous points on the contour of the leader which controls the movement of the jack during the operation of the tool.

Other objects of the invention aim to provide improved means for supporting the leader, an improved jack for supporting the work, and improved means for securing the jack upon the leader support.

To the accomplishment of these objects and such other as may hereinafter appear, as will readily be understood by those skilled in the art, the invention comprises the features and combinations of parts herein-after described and then particularly pointed out in the appended claims.

The preferred form of the invention is illustrated in the accompanying drawings, in which:

Figure 1 is a view, in plan, of the leader support, with a shoe jack assembled therewith, the parts being shown in unclamped relation to each other; Fig. 2 is a view, in side elevation, of the apparatus shown in Fig. 1 the parts being in the same relation to each other and a shoe last being shown on the jack by dash lines; Fig. 3 is a view, in central longitudinal section, through the leader support with a leader indicated in position below the support; Fig. 4 is a view, in central transverse section, through the leader support looking toward the right in Fig. 1; Fig. 5 is another transverse sectional view through the leader support taken at one of the leader clamping bushings; Fig. 6 is a view, in elevation, and with the toe post partly in section, of the shoe supporting jack, the central portion also being shown separately, in plan; Fig. 7 is a sectional view on the line 7-7 of Fig. 6; and Fig. 8 is a sectional view on the line 8-8 of Fig. 6.

In the embodiment of the invention illustrated in the drawings, and referring first to Figs. 6 to 8, the jack comprises a toe post 10 provided with a fore-part pad or rest 12 of any suitable construction, a heel post 14 having the usual last pin 16, and a base bar or frame piece 18. These three parts form separate units and are readily disconnected one from the other. Their assembled position, permitting quick adjustment and providing for locking the jacked shoe, will now be explained.

The base bar 18 is formed of a relatively thin metal plate the opposite ends of which are received in channel-shaped housings carried by the toe and heel posts. The toe post housing 20 is integral with the toe post, extending inward horizontally from its base. The heel post housing 22 is received in a vertical slot 24 formed by the forks 26 at the lower end of the heel post. The heel post is connected to its housing by means of two horizontal pins 28 and 30 seated in bosses on

one face of the housing with their ends engaged in a curved slot 32 in the adjacent fork 26. The slot 32 is arcuate and is struck from a center on the heel post located at 5 substantially the point where the comb of the last rests. With this construction the toe and heel posts may be slid toward and from each other on the base bar to position them for the size of shoe being jacked. The 10 limits of this sliding movement are determined by pins 34 taking into slots on bars 36 carried, respectively, by the housings and the base bar. After the last, on which the shoe is built, has been placed on the last 15 pin 16 with its toe end resting on the pad 12, a tool of suitable form is engaged with a pair of hooks 38 at the lower edges of the forks 26 and the last pin is tipped forward by pulling the lower end of the heel post 20 outward. This places pressure on both the toe and heel posts and causes the housings to bind on the upper and lower edges of the base bar. The three parts of the jack are thus locked together and it may be transported from one machine to another without 25 danger of disturbing the position of the shoe thereon.

Before locking the last to the jack its longitudinal position is adjusted, by relative 30 movement of the toe and heel posts on the base bar, to bring two known points at the toe and heel of the last bottom, or insole of the shoe, to a definite position with relation to a centering pin 40 which projects laterally from the central portion of the base bar. The manner in which these positioning 35 points are determined and the apparatus used in locating the work on the jack form the subject matter of separate applications 40 Serial Nos. 587,939 and 587,940 filed of even date herewith. For the purposes of this application it is merely requisite to understand that the final location of the work, before the jack is locked, is such that the pin 40 lies 45 in a vertical plane equidistant from the two known positioning points.

Having thus positioned the work on the jack, the jack is taken to one of the machines of the automatic shoe making system and 50 seated on a jack support with which each machine is provided. The jack support 42 is in the form of an inverted dish-shaped spider (see Figs. 1 to 5) having a lower face 43 for sliding engagement with the surface of a supporting table (not shown), and will hereinafter be designated as the "skate." The skate sustains a sole-shaped leader 44, through which its movement over the table is controlled, and is provided with a vertically slotted plate 46 for receiving the jack centering pin 40 and thus locating the jack in a definite longitudinal position on the 55 skate. The relation of the centering device 46 to the leader 44 is such that when the jack is assembled and clamped on the skate the

peripheral edge of the work on the jack is superposed with exactness above the controlling surface 45 of the leader.

The means for clamping the jack on the skate is utilized also for clamping the leader 70 on the skate. The skate is in two parts and comprises the spider, or table engaging portion 42 and a hollow frame 48 (Figs. 3 to 5) seated in a central opening in the spider. The frame 48 is secured to the spider by 75 four screws 50 (Figs. 1 and 5). The frame 48 comprises a rear wall 52 to a central lug on which the centering device 46 is secured, a front wall 54 and end webs 56 having corner posts 58, the whole presenting a longitudinal channel formation for receiving the jack (see Fig. 1). Each end web 56 is bored vertically to receive an expanding bushing 60 which extends below the lower face of the frame 48 and into holes previously 80 formed in the central web of the leader 44. Each bushing receives an axially arranged pin 62 having a conical head 64 at its lower end and a flat head 66 at its upper end. Two horizontal plates 68, having central diagonal meeting edges forming a slot 69 (Fig. 1), are forked at their outer ends and engage under the heads 66 of the bushing pins. With this construction, if downward 85 pressure is applied at the meeting ends of the plates 68 they fulcrum on the inner walls 70 of the end webs and thus simultaneously raise the pins 62. Such a movement of the pins expands the bushings and clamps the leader firmly to the skate. When in position the two bushings are equidistant from the centering device 46.

Before describing the mechanism for depressing the inner ends of the plates 68 the means for clamping the jack in position 90 will be described. At the forward side of the channel formed by the frame walls 52 and 54 are two vertically arranged plates 72, their meeting edges being central and opposite the co-operating jack positioning 95 devices 40 and 46. The outer end of each plate 72 is secured to a post 58 in the following manner. The post is bored horizontally at 74 (Fig. 5) and has seated therein a block 76 having a hemi-spherical head. The plate 72 has a socket into which said head takes and the parts are held yieldingly together by an axial pin 78 held in position by a spring washer 80. The extreme outer end of the plate 72 is provided 100 with a pressure member in the form of a half-round 82 arranged vertically with its rounded surface against the plate. Two rivets 84, seated in enlarged holes in the plate 72, hold the half round in position 105 but permit it to rock sidewise. The plates 72 normally have the slight angular relation shown in Fig. 1 but when outward pressure is applied at their meeting ends, they fulcrum on the blocks 76 and cause the 110

half-rounds 82 to engage the front face of the toe post housing 20 on the jack and the front fork 26 of the heel post. This pressure forces the jack against the rear wall 52 of the skate frame and clamps it to the skate by the frictional binding pressure thus created. As described, the mounting of the half-rounds 82 permit them to rock, as the angle of the plates 72 changes, while still maintaining a firm bearing on the jack.

A common actuator, in the form of a hand lever 86 (Figs. 1, 2 and 4), is employed to shift both pairs of plates 68 and 72. This hand lever is carried loosely by the forward end of a headed pin 88 which is passed horizontally through an opening at the meeting edges of the plates 72, through a hole in the wall 54, and through the upper end of a vertical lever arm 90 pivoted to rock on a pin 92 carried by two lugs 94 depending from the front side wall 54. The head of the lever arm 90 is provided with oppositely disposed lateral wings 96 and this head is held against the rear face of the hand lever by lock nuts 98 on the pin 88. The hand lever has two diametrically disposed cam surfaces 100 which, as the lever is rotated, engage the wings 96. The lever arm 90 has a connected horizontal arm 102 (Fig. 4) the rear end of which is forked and embraces the shank of an inverted T-shaped piece 104 (Fig. 3) which extends through the oblique slot 69 at the meeting edges of the plates 68 and has a head 106 crossing said slot.

On turning the hand lever 86 to the left the cams 100 act first to draw the pin 88 forward until the half-rounds 82 meet the jack. The resistance thus created will cause the lever 90—102 to be moved in a counter-clockwise direction viewing Fig. 4, before the pin 88 reaches its final forward position. The final pressure on the jack to clamp it against the rear gaging wall 52, and the final pressure on the T-piece 104 to fully expand the bushings 60, thus occur simultaneously. This sequence may vary because the exact operation depends on the amount of resistance encountered as the cams 100 are rotated and the time when this resistance becomes effective. A single movement of the hand lever thus clamps or unclamps the leader and jack, as heretofore described. The angular movement of the hand lever is limited by the engagement of a surface 108 thereon with a stop 110 mounted on the skate (Figs. 1 and 2).

It will be observed that a single turn of the hand lever 86 clamps or unclamps the jack and, because of the open channel formation of the central frame 48 of the skate, the jack can instantly be lifted from one skate and as readily be assembled with another in a different machine. The lateral position of the jack relative to the leader

is determined by the gaging surface formed by the inner face of the rear frame wall 52 and the thickness of the jack post housings 20 and 22. These housings are so proportioned that the longitudinal datum lines on the work and leader, referred to in said co-pending applications, both lie in the same vertical plane when the jack is clamped against the wall 54. The longitudinal position of the jack relative to the leader is determined by the centering devices 40 and 46, each of which bears the same relation to known points on the work and leader respectively.

Those skilled in the art will recognize that the jack may be employed for supporting a last, a portion of a shoe, or a complete shoe, and that any of these pieces of work may have an operation performed thereon by the shoe machine which supports the leader and skate with which the jack is assembled. The scope of the invention, therefore, is not limited to a utilization of the apparatus for shoe building operations alone but is broad enough to include other shoe making or shoe finishing processes.

Obviously changes may be made in the form, character and relation of the parts within the scope of the invention, characterizing features of which are set forth in the claims by the intentional use of generic terms inclusive of various modifications.

What is claimed as new, is:

1. Shoe making apparatus of the character described having, in combination, a frame for supporting a separate leader and a separate jack, means on the frame and the jack adapted to co-operatively engage to locate the jack in a definite position on the frame relative to the leader, and means for clamping the jack in such position.

2. Shoe making apparatus of the character described having, in combination, a frame, a leader and a jack removably mounted on said frame, and separate means for securing said leader and jack to the frame.

3. Shoe making apparatus of the character described having, in combination, a frame, a leader and a jack removably mounted on said frame, separate securing means for said leader and jack, and a common actuator for operating said securing means.

4. Shoe making apparatus of the character described having, in combination, a frame, a sole-shaped leader supported by said frame, a jack having a centering device in definite relation to points on the area of the work supported by the jack, a co-operating centering device on the frame having a like relation to homologous points on the leader, and means for securing the jack to the frame with said centering devices in co-operative engagement.

5. Shoe making apparatus of the character described having, in combination, a skate, a leader removably secured to the under side of said skate, and a unit jack removably secured to the upper side of said skate. 70
6. Shoe making apparatus of the character described having, in combination, a skate having means to support a leader, a jack removably supported on the skate, and means for gaging the location of the jack on the skate when positioned thereon. 75
7. Shoe making apparatus of the character described having, in combination, a unit jack for mounting a shoe to be operated upon; a skate; a leader supported by the skate adapted to be engaged and rotated by driving elements of a shoe machine and shaped to provide a controlling surface which, in plan, is like the peripheral portion of the shoe to be operated upon by the tool of the shoe machine; and means for instantly positioning the jack on the skate with said periphery of the shoe superposed on said controlling surface of the leader. 80
8. Shoe making apparatus of the character described having, in combination, a unit jack for mounting a shoe to be operated upon; a skate; a leader supported by the skate adapted to be engaged and rotated by driving elements of a shoe machine and shaped to provide a controlling surface which, in plan, is like the peripheral portion of the shoe to be operated upon by the tool of the shoe machine; and devices carried by the jack and the skate which, when engaged in positioning the jack on the skate, locate the shoe longitudinally relative to the leader for the correct operation of the tool at the ends of the shoe. 90
9. Shoe making apparatus of the character described having, in combination, a jack for mounting a shoe to be operated upon; a skate; a leader supported by the skate adapted to be engaged and rotated by driving elements of a shoe machine and shaped to provide a controlling surface which, in plan, is like the peripheral portion of the shoe to be operated upon by the tool of the shoe machine; gaging means on the jack bearing a definite relation to preselected points on said periphery of the shoe, and co-operating gaging means on the skate bearing the same relation to homologous points on the controlling surface of the leader, which means when co-operatively engaged insure a predetermined longitudinal and lateral relation between the shoe and leader. 100
10. In shoe making apparatus of the character described, a skate presenting an open channel formation at its upper face and dish-shaped at its lower face, means in said channel for clamping a jack to the skate, and means at said lower face for clamping a leader below the jack. 110
11. In shoe making apparatus of the character described, a skate of inverted dish-shaped form having a surface for sliding engagement with the table of a shoe machine, and provided with means for clamping a leader and a unit jack thereon in a single definite relation. 120
12. In shoe making apparatus of the character described, a skate in the form of an inverted dish-shaped spider having a central opening, and a unit jack supporting 75 frame seated in said opening. 125
13. In shoe making apparatus of the character described, a skate having a surface for sliding engagement with the table of a shoe machine, a central supporting frame, and devices carried by said frame for securing a leader and a unit jack to the skate in a single definite relation. 130
14. In shoe making apparatus of the character described, a skate having a surface for sliding engagement with the table of a shoe machine, a central supporting frame, devices carried by said frame for securing a leader and a jack to the skate, and a common actuator for said devices. 140
15. In shoe making apparatus of the character described, a skate having a surface for sliding engagement with the table of a shoe machine, a central supporting frame, clamping devices carried by said frame for a leader and a jack, and interconnected means for operating said clamping devices. 145
16. In shoe making apparatus of the character described, a skate having a surface for sliding engagement with the table of a shoe machine, a central supporting frame, devices carried by the frame for clamping a leader and a jack thereto, and a cam lever for operating said devices. 150
17. A jack for shoe machinery having, in combination, a base piece, adjustable housings mounted on the opposite ends thereof, heel and toe posts supported by said housings, and means for causing said housings to bind on the base piece in a selected position 155 thereon. 160
18. A jack for shoe machinery having, in combination, a base piece, two slideable housings thereon supporting heel and toe posts, and means for exerting pressure through the jacked shoe to clamp the housings against movement on the base piece. 165
19. A jack for shoe machinery having, in combination, a base piece comprising a vertically arranged strip, a centering pin projecting laterally from the central portion of one side thereof, and a heel post and a toe post at opposite sides of said pin and adjustable on the base piece toward and from said pin. 170
20. A jack for shoe machinery having, in combination, a strip on edge, housings slidably mounted at each end of said strip, a toe post rising from one housing, a heel post rising from the other housing and having 175

a forked lower end straddling the housing, and means connecting said heel post to its housing permitting it to be tilted toward the toe post.

- 5 21. A jack for shoe machinery having, in combination, a strip on edge, housings slidably mounted at each end of said strip, a toe post rising from one housing, a heel post rising from the other housing and having 10 a forked lower end straddling the housing, means connecting said heel post to its housing permitting it to be tilted toward the toe

post, and means for retaining the heel post in its tilted position.

22. A jack for shoe machinery having, in combination, a strip on edge, channel shaped members embracing each end of said strip, and slidable thereon, heel and toe posts for supporting a shoe, sustained by said members, a centrally located member to which 15 said posts are adjusted, and means acting through the shoe for locking the posts in any desired position of adjustment.

MARK E. FERNALD.
